UNITED STATES PATENT OFFICE.

EDWIN E. SLICK, OF PITTSBURG, PENNSYLVANIA.

MILL FOR ROLLING IRREGULAR SHAPES.

No. 873,463.

Specification of Letters Patent.

Patented Dec. 10, 1907.

Application filed March 3, 1905. Serial No. 248,233.

To all whom it may concern:

Be it known that I, EDWIN E. SLICK, of Pittsburgh, Allegheny county, Pennsylvania, have invented a new and useful Mill for Rolling Irregular Shapes, of which the following is a full, clear, and exact description, reference being had to the accompanying drawings, forming part of this specification, in which—

10 Figure 1 is a plan view of my improved mill; Figs. 2, 3 and 4 are diagrammatic side elevations showing the lines of feed in the successive directions; Fig. 5 is a partial front elevation of the roughing rolls; Fig. 6 is a similar view of the edging rolls; Fig. 7 is a partial front elevation of the third set of rolls; and Figs. 8 and 9 illustrate the passes in the finishing and bending rolls.

20 My invention relates to the rolling of irregular shapes such as angles, channels, beams, rails, etc., and the object of the invention is to provide a simple and compact arrangement of rolls which will give a large output with low labor cost and without the use of 25 laterally or sidewise moving tables, or the necessity for laterally moving the metal sidewise on the tables, except for the roughing rolls.

30 In the drawings, 2 represents a continuous heating furnace in which the billets or blooms are heated and shoved out onto the vertically-movable table 3 for the three-high roughing rolls 4, 5 and 6. A vertically-movable table 7 is also placed on the other side of 35 this three-high mill, and it will be understood that these tables may be either tilting or vertically-moving tables. On this roughing set of rolls the metal is preferably given three passes as shown in Fig. 5.

40 In the form shown where I have illustrated the mill as arranged for rolling angles, a represents the metal passing through the first open pass between the middle roll 5 and the lower roll 6. The rear table 7 is then lifted 45 with the metal upon it and the metal is shifted sidewise on the table and passed back as shown at b and received on the front table 3 which is in lifted position. The front table is then lowered and the metal shifted sidewise and passed forward from the third pass 50 as shown at c, this pass beginning the formation of the ridge to form the corner of the angle. In this pass where angles are rolled, I preferably employ the adjustable guides 8 55 by which the length of the two legs may be adjusted as desired. The metal passing

through this third pass of the roughing rolls is received on the rear table 7 in its lower position, and then feeds forwardly over the conveyer table 9 to the two-high set of rolls 60 10 and 11 shown in Fig. 6. These rolls contain edging passes, the metal being shown at d. These edging passes are of different height and set the width of the blank. The metal is turned in passing from the first 65 three-high set to the edging set of rolls, so that it enters the edging rolls in a plane at right angles to that of the first or roughing set. After passing through one of the passes of the edging rolls, the metal feeds forwardly 70 on the upwardly-inclined feed-table 12 to the three-high set of rolls, 13, 14 and 15, shown in Fig. 7. The metal passes through a pass between the upper and middle rolls as shown at e, Fig. 7, and in the case of angles 75 the adjustable side guides 16 and 17 are used to maintain the length of the legs in accordance with the point of the ridge. After passing through this pass, the metal drops down upon the feed table 18 and feeds back 80 through a pass between the middle and lower rolls as shown at f, Fig. 7, this pass also having adjustable side guides. The table or trough 18 is preferably inclined downwardly 85 toward the rolls. The metal passing back through this three-high set enters a feed-table or trough 19 which extends at an angle to the feed-table 12. The metal in passing from the three-high mill into this trough 19 is bent slightly, and will also be bent somewhat in entering the three-high set of rolls 90 20, 21 and 22.

I have shown the table 19 as inclined upwardly as well as sidewise, so that the metal enters the upper pass and is bent in feeding 95 in. The metal passes through as shown at g, Fig. 8, and drops upon a table or support 23 where it is moved sidewise and feeds back through the lower finishing pass shown at h, Fig. 8. This pass not only reduces the 100 metal, but bends the legs somewhat out of the flat plane in which they have previously been rolled. After passing back through the pass h, the metal feeds over the trough or feed table 24 to the final set of two-high rolls 105 25 and 26 containing the open passes, the metal feeds through one of these bending passes as shown at k by which the angle is bent to its final form, and thence feeds forward on the table 27, to hot bed 34.

In the form shown the three-high rolls, 4, 5 and 6 are in endwise alinement with the

rolls 20, 21 and 22, and both are driven from the same set of pinions 28 actuated from the engine 29. The three-high set of rolls 13, 14 and 15 are shown as in line with the two-high rolls 25 and 26, both sets being driven from the pinions 30 actuated by engine 31. I have shown the other two-high rolls 10 and 11 as driven by pinions 32 actuated by a shaft having a rope-drive connection 33 with the main shaft of engine 29. The driving connections of these sets of rolls may, however, be varied in any desirable manner.

I have shown the first three-high set of rolls, the edging set of rolls, and the second set of three-high rolls as arranged in tandem, and prefer this arrangement. The second set of three-high rolls may, however, be out of line with the edging rolls, giving the feed-table 12 a sidewise inclination and reducing the angle of the trough or feed-table 19. The first set of three-high rolls may be out of endwise alinement with the three-high set 20, 21 and 22, and the bending rolls may be out of alinement with the three-high set 13, 14 and 15, though I prefer the arrangement shown. The first pass in the third or fourth sets may be between the middle and bottom rolls, and the back pass between the middle and top rolls.

30 The advantages of my invention result from the peculiar arrangement of the mills whereby a compact easily operated mill is provided. The use of laterally or sidewise moving tables is avoided, and no movable tables are needed except for the roughing rolls. The metal is not carried sidewise on the laterally moving table to transfer it from one set of rolls to another out of line therewith as the inclined trough between the third and fourth sets of rolls avoids this. A large output may be obtained at low expense.

It will be noted that after the metal has fed forwardly from the roughing set of rolls, there is no transfer bodily sidewise of the metal in parallel lines. In feeding the metal forward through an upper pass of either of the succeeding three-high rolls and then back through a lower one out of vertical alinement therewith, the end of the metal is merely 45 moved laterally into line with the next pass without moving the whole piece bodily sidewise.

The set of edging rolls may be omitted, and many other variations may be made in the form and arrangement of the mills without departing from my invention.

I claim:—

1. In a rolling-mill plant, a three-high set of roughing rolls, another three-high set of

rolls in the rear of the same, a third set of 60 three-high rolls on the same side of the rear set as the roughing mill, and a laterally-inclined feed-device between the rear set and the third set of rolls; substantially as described.

65

2. In a rolling-mill plant, a three-high set of roughing rolls, another three-high set of rolls in the rear and in line with the roughing set, a third three-high set of rolls on the same side of the second set as the first set, and a laterally-inclined feed-device leading from the second set to the third set; substantially as described.

70

3. In a rolling-mill plant, a three-high set of roughing rolls, another three-high set of 75 rolls in the rear and in line with the roughing set, a third three-high set of rolls on the same side of the second set as the first set, a laterally-inclined feed-device leading from the second set to the third set, and a fourth set of 80 rolls in the rear of and in line with the third set of rolls; substantially as described.

80

4. In a rolling-mill plant, a three-high roughing set of rolls, a second set of three-high rolls in the rear thereof and in line with 85 the roughing set, a third set of three-high rolls on the same side of the second set as the first set, a laterally-inclined feed-device leading from the second set to the third set, and a two-high set of rolls in the rear of the third 90 set and in line therewith; substantially as described.

90

5. In a rolling-mill plant, a three-high roughing set of rolls, a second set of three-high rolls in the rear thereof and in line with 95 the roughing set, a third set of three-high rolls on the same side of the second set as the first set, a laterally-inclined feed-device leading from the second set to the third set, a two-high set of rolls in the rear of the third 100 set and in line therewith, and an edging set of rolls in the line of feed between the first and second sets of rolls; substantially as described.

100

6. In a rolling-mill plant, a three-high set 105 of roughing rolls, another three-high set of rolls in the rear of the same, a third set of three-high rolls on the same side of the rear set as the roughing mill, and a laterally and vertically-inclined feed-device between the 110 rear set and the third set of rolls; substantially as described.

110

In testimony whereof, I have hereunto set my hand.

EDWIN E. SLICK.
